UNITED STATES PATENT OFFICE.

ERICH H. LICHTENBERG, OF MILWAUKEE, WISCONSIN, ASSIGNOR TO KOEHRING COMPANY, OF MILWAUKEE, WISCONSIN, A CORPORATION OF WISCONSIN.

CONCRETE MIXING AND SPREADING MACHINE.

Application filed March 27, 1926. Serial No. 97,933.

The primary aim of this invention is to produce a machine for building concrete roads, which is designed to lay down the concrete aggregates the entire width of the road to be built, and in a progressively continuous manner. There is a growing tendency in this country, in highway building operations, to construct roads of uniform minimum widths and where an especially wide highway is to be produced accepted practice makes advantageous the building of the wider highway of a width constituting a multiple of the width of the road of minimum accepted transverse area.

15 The foregoing conditions and developments of the art of road building renders desirable the use of a machine having sufficient capacity, and suitably constructed to mix the concrete aggregates, and feed them to 20 the road subgrade over the entire width of the same, and the machine hereinafter described in detail is intended to do this work.

More specifically presented, my machine embodies a portable mixing plant consisting 25 of a plurality of concrete mixers supplied by a corresponding number of feeding hoppers. Associated with the mixing plant is a loading device common thereto adapted to hoist batch boxes containing the dry aggregates to be mixed, carry the said batch boxes to a point above the feeding hoppers, discharge them into said hoppers, and by their discharging operation set into action certain control means governing the action 30 of the discharge chutes of the mixers.

Also there is associated with the mixing plant a distributing means preferably in the form of a distributing hopper which extends the whole width of the pavement or road section to be laid. The mixed concrete aggregates are thus fed to the road section sub-grade and provisions are made whereby the concrete is laid down in a layer, or of 40 a thickness, substantially that required for 45 the completed pavement.

The invention includes certain detail interlocked control mechanisms which are essential for cooperative functioning of the parts of my machine, and the machine is more 50 over designed to be advanced as a complete

operating unit or plant, by the loading unit which is equipped with operating traction means for the purpose.

With the foregoing in view, a full understanding of the invention will be had on 55 reference to the following description in conjunction with the annexed drawings in which:—

Figure 1 is a side elevation of a concrete loading, mixing, and distributing machine, 60 embodying the invention.

Figure 2 is a top plan of the same, showing an industrial railway for bringing up the aggregates from a central supply plant, ready to be handled by my machine. 65

Figure 3 is a sectional view, showing more clearly the distributing hopper and leveling means therein, together with the finishing roller associated therewith.

The general operating features of my 70 machine may be set forth comprising the loading device or apparatus A which comprises a rotary crane 1, having a boom 2 together with hoisting tackle means 3, operatively connected with an automatic grapple 75 4, which may be of the type set forth in Letters Patent of Tranaas, No. 1,565,688, issued December 15, 1925. The automatic grapple 4 is adapted to be engaged with a batch box 5 that may readily be hoisted 80 from the truck of an industrial car operating on the tracks 6, seen in Figure 2. The operator at the crane 1 may thus control the discharging of the box 5 by manipulation of the hoisting cables 3, and a suitable 85 grapple operating cable associated therewith.

The loading means or crane just described is mounted upon a traction base 7 adapted to be driven from the power plant of the loading device which includes the crane 1. Under these conditions, the crane, being self propelling, is adapted to be connected up to 90 propel the mixing and distributing devices of the invention. For this purpose I provide the crane 1 with draft means 8, attached to a 95 portable frame or traction base 9, equipped with wheels 10 at the front end and traction belts or multiplanes 11 at the rear.

Upon the traction or portable support 9 is mounted the mixing plant which comprises 100

a plurality of mixers 12 having discharge chutes 13 to discharge the mixers into a distributing hopper 14. Feed hoppers 15 at the charging ends of the mixers 12 receive 5 the batches of concrete aggregates fed to the mixers and direct said aggregates into the drums of said mixers.

Each mixer 12 will be operated by its own engine 16, disposed beneath the hopper 15 or otherwise suitably located and having a driving shaft 17 geared to the drum of the associated mixer. Or if desired, a single engine may operate the two mixers 12.

15 The distributing hopper 14 is common to the two mixers to receive the mixed concrete aggregates therefrom when the latter are discharged. Said hopper 14 has a restricted discharge opening 18 at its lowermost portion and of a length corresponding to the full width of the road or section of road that is being laid down by the machine. The said restricted discharge opening 18 is controlled by a discharge door 19 20 adapted to be opened to a greater or less extent under the control of a lever 20 having an arm 21 attached by a rod 22 to the door 19, which restrictively, or retardingly, permits the aggregates to pass down upon 25 the sub-grade. The thickness of these aggregates may thus be regulated. The lever 20 may be locked in different positions by cooperation of a latch thereon with a locking sector.

30 35 In rear of the hopper 14 may be provided a finishing device in the form of a strike off, or finishing roller 24 connected by links 25 to the hopper supporting structure.

40 Mounted in the upper portion of each feeding hopper 15 is a strip plate 26 pivoted to an operating shaft 27 and adapted to perform two functions. First, the shaft 27 has an arm to operate a trip rod 28 connected with the discharge chute 13 adjacent 45 to said feeding hopper 15. When the loaded batch box 5 is discharged into the hopper 15 the trip plate 26 is struck by the gravitating aggregates and moves the discharge chute 13 into a non-discharging position in relation to its mixer 12. Secondly, 50 the trip rod 28 actuated by the trip plate 26 is connected with a batchmeter 29 associated with the adjacent mixer 12, and starts said batchmeter into operation. Those versed in the art are fully advised as to the 55 action of batchmeters so the operation thereof need not be described. Said batchmeter, however, when tripped by the rod 28 is set into action to control the mixing of the aggregates simultaneously fed into the mixer, to prevent discharge of these aggregates until an elapsed period of mixing thereof in the mixer 12 is completed. Then the batchmeter causes operation of the discharge chute 60 65 13 to place it in the discharge position and

empty the mixer 12 with which it is cooperating. This batchmeter control may be similar to that set forth in Letters Patent of Robb No. 1,370,497, issued March 1, 1921, except that the trip plate 26 trips the batchmeter into action instead of the latter being so tripped by a loading skip like that set forth in said patent. Or the operating means for actuating the chute 13 from the batchmeter 29 may be as set forth in the application of Webb, Serial No. 5,827, filed January 30, 1925.

Regarding the distributing means including the hopper 14, it is notable that said hopper is made in sections including the end sections 14^a adapted to be removed. The end sections have end plates 14^b adapted to be secured to the middle section of the hopper, if the road which is to be laid is substantially of the width of the middle section alone.

Mounted in the hopper 14 and upon its end plates 14^b, as well as intermediate bearing brackets 30 is a sectional shaft which carries a series of screws or spiral blades 31 arranged on the shaft to be driven thereby, and adjacent of which blades extend in reverse directions. The purpose of these blades 31 is to level the mixed aggregates in the hopper, that is to spread them evenly over the bottom of the hopper.

The spiral blades 31 are driven by driving shafts 32 geared to the ends of the blade shaft 33, and the shafts 32 are driven from the engines 16.

100 The complete operation of my machine may now be set forth.

The dry aggregates for the concrete batches to be fed to the mixers 12 are supplied by batch hoppers 5 brought up on the industrial railway or railways 6. The crane 1 elevates a batch hopper 5 to a point above a feeding hopper 15, discharges the contents of the batch hopper into the feeding hopper and thereby sets the discharge chute 13 of the associated mixer 12 in non-discharging position by action of the trip plate 26. One of the mixers is thus caused to operate to mix a batch of concrete, and under the control of its batchmeter 29 discharges said batch into the distributing hopper 14. Meanwhile the crane 1 supplies a batch box load of aggregates to the other hopper 15 and operates its batchmeter and trip plate in the same manner as previously set forth. 110 Because of the great capacity of my machine for mixing, it is contemplated that the traction means 7 of crane 1 may be started into operation to move the whole combined machine progressively forward at a slow rate of speed, during which the operations of feeding aggregates to the mixers, mixing the aggregates in the mixers, discharging the aggregates to the sub-grade and finishing the aggregates after delivered to the sub- 115 120 125 130

grade in a predetermined thickness may continuously be performed in the progressive advance of the whole machine.

Having thus described my invention, what I claim as new, and desire to cover by Letters Patent, is:—

1. In a paving machine, in combination, a portable traction support, a mixer thereon, means for advancing the support over a road 10 sub-grade to be paved, a distributing hopper of a width substantially that of the road section to be laid on the sub-grade and having a restricted discharge outlet at its bottom, means for discharging from the mixer into 15 said hopper a quantity of mixed aggregates partially filling the hopper to provide a body of supply aggregates to be laid on the sub-grade, and means for leveling within the hopper the aggregates discharged into the hopper 20 so they will be uniformly supplied to the distributing portion of said hopper.
2. In a paving machine, in combination, a portable traction support, a mixer thereon, means for advancing the support over a road 25 sub-grade to be paved, a distributing hopper of a width substantially that of the road section to be laid on the sub-grade, means for discharging from the mixer into said hopper, and means for leveling the aggregates discharged into the hopper so they 30 will be uniformly supplied to the distributing portion of said hopper, the means for advancing the machine over the road sub-grade comprising a self propelling loader 35 embodying means to supply the mixer with aggregates.

3. In a paving machine, in combination, a portable traction support, a mixer thereon, means for advancing the support over a road 40 sub-grade to be paved, a distributing hopper of a width substantially that of the road section to be laid on the sub-grade, means for discharging the mixer into said hopper, and means for leveling the aggregates discharged 45 into the hopper so they will be uniformly supplied to the distributing portion of said hopper, the means for advancing the machine over the road sub-grade comprising a self propelling loader embodying means to 50 supply the mixer with aggregates, the said distributing hopper having a distributor extending substantially its entire length and means for regulating the operative area of said opening.

5. 4. In a paving machine, in combination, a portable traction support, a mixer thereon, means for advancing the support over a road sub-grade to be paved, a distributing hopper of a width substantially that of the 55 road section to be laid on the sub-grade and adapted to hold a supply of material to be distributed, means for discharging the mixer into said hopper, and means for leveling the aggregates discharged into the hopper so they will be uniformly supplied to the dis-

tributing portion of said hopper, the distributing hopper comprising sections whereby its operative length which is substantially that of the width of the road being laid may be increased or decreased to conform 70 with said road width.

5. In a paving machine, in combination, a portable traction support, a mixer thereon, means for advancing the support over a road sub-grade to be paved, a distributing 75 hopper of a width substantially that of the road section to be laid on the sub-grade, means for discharging the mixer into said hopper, and means for leveling the aggregates discharged into the hopper so they 80 will be uniformly supplied to the distributing portion of said hopper, the distributing hopper comprising sections whereby its operative length which is substantially that of the width of the road being laid may be 85 increased or decreased to conform with said road width, the leveling means in the hopper being also made in sections so that it may be correspondingly changed as to length to conform with the length of the 90 hopper.

6. A distributor for road paving machines, comprising a hopper adapted to contain mixed aggregates, and having a restricted distributing opening capable of 95 controlling the flow of material therefrom and a leveling device in said hopper to uniformly spread mixed aggregates supplied to the hopper to an even depth over the operating area of said distributing opening. 100

7. A distributor for road paving machines, comprising a hopper for containing a large distributable quantity of mixed aggregates and equipped with a distributing opening and a leveling device in said hopper to uniformly spread mixed aggregates supplied to the hopper over the operating area of said distributing opening, the hopper being made of sections so it may be shortened or lengthened and the leveling means 110 being likewise made in sections for the same purpose.

8. A distributor for road paving machines, comprising a hopper adapted to contain mixed aggregates and having a distributing opening and a leveling device in said hopper to uniformly spread mixed aggregates supplied to the hopper over the operating area of said distributing opening, said leveling means consisting of a spiral 115 blade device disposed above the distributing opening, and means for retarding the passage of aggregates out of said distributing opening so the hopper will hold a large amount of mixed aggregates to feed therefrom. 120

9. A distributor for road paving machines, comprising a hopper having a distributing opening and a leveling device in 125 said hopper to uniformly spread mixed ag-

gregates supplied to the hopper over the operating area of said distributing opening, said leveling means consisting of a spiral blade device disposed above the distributing opening, and means for retarding the passage of aggregates out of said distributing opening, the hopper and the leveling means being made in sections so as to be shortened

or lengthened, and the retarding aforesaid consisting of a door at the distributing opening with means to open said door to different degrees to thereby change the operative area of the distributing opening.

In testimony whereof I affix my signature.

ERICH H. LICHTENBERG.
